(57) **CLAIM**

The ornamental design for a cellular phone with a dynamic display on the screen thereof, as shown and described.

DESCRIPTION

FIG. 1 is a front, right perspective view of the cellular phone with a dynamic display on the screen thereof showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom view thereof.

The broken lines show environmental elements only and form no part of the claimed invention.
